UNITED STATES PATENT OFFICE.

FRANK E. SMALL, OF BROOKLYN, NEW YORK, ASSIGNOR OF ONE-HALF TO FREDERICK E. SMALL, OF BOSTON, MASSACHUSETTS.

DESIGN FOR A HANDKERCHIEF-CLIP.

SPECIFICATION forming part of Design No. 27,360, dated July 13, 1897.

Application filed April 10, 1897. Serial No. 631,639. Term of patent 7 years.

To all whom it may concern:

Be it known that I, FRANK E. SMALL, a citizen of the United States, residing at Brooklyn, Kings county, and State of New York, have invented and produced a new and original Design for a Handkerchief-Clip for Bicycles, of which the following is a specification.

As shown in the drawings, the leading or material feature of my design consists of the semicircular-shaped spring-clamp 6, provided with the finger-shaped spring-clip 7.

What I claim as new, and desire to secure by Letters Patent, is—

The design for a handkerchief-clip for bicycles, substantially as herein shown and described.

In testimony whereof I have signed my name to this specification in the presence of two subscribing witnesses.

FRANK E. SMALL.
